ALFRED R. HUNTINGTON, OF RIVERSIDE, CALIFORNIA, ASSIGNOR OF ONE-THIRD TO RICHARD G. MANIFOLD AND ONE-THIRD TO CHARLES O. POOLE, BOTH OF RIVERSIDE, CALIFORNIA.

ELECTRIC HEATER.

1,287,323.

Specification of Letters Patent. Patented Dec. 10, 1918.

Application filed March 21, 1918. Serial No. 223,843.

To all whom it may concern:

Be it known that I, ALFRED R. HUNTINGTON, a subject of Great Britain, residing at Riverside, in the county of Riverside and State of California, have invented new and useful Improvements in Electric Heaters, of which the following is a specification.

This invention relates to improvements in electric heaters, and the primary object 10 thereof is to provide a simply constructed, comparatively small, inexpensive, compact, durable, and highly efficient electric heater, which is attractive and ornamental in appearance and capable of expeditiously producing relatively greater heat at less fuel consumption, as compared to heaters of the present-day type.

An object of the invention is to provide in a heater of the above-mentioned character, a 20 reflector or radiator of such shape and construction that heat produced by a heating element associated with the reflector will be caused to radiate from the reflector in substantially parallel lines, such parallel and outward projection of heat being highly desirable and providing for effective heating 25 of the zone immediately in front of the heater.

The invention further consists in the particular combination, inter-relation, relative arrangement, construction, association of the several parts, elements and features of the heater, as illustrated in the accompanying drawings, described in the following specification, and finally pointed out in claims. Other objects and advantages will appear during the course of the following description.

In the drawings:

40 Figure 1 represents a front elevation of a heater constructed in accordance with this invention;

Fig. 2 represents a vertical sectional view taken on the line x^2-x^2 of Fig. 1;

45 Fig. 3 represents a fragmentary view of the heating element showing the same in section and the manner of securing the coil to the supporting means therefor;

Fig. 4 represents a fragmentary vertical 50 sectional view of a modified form of the invention in which the modification relates to the heating element;

Fig. 5 is a fragmentary front elevation of

the form of heating element disclosed in Fig. 4 showing the same broken away for the sake 55 of clearness;

Fig. 6 represents a vertical fragmentary sectional view of another modified form of the invention as regards the heating element; and

Fig. 7 represents a detail front elevation 60 of the heating element disclosed in Fig. 6.

Referring particularly to the drawings and specifically to Figs. 1, 2 and 3 thereof, the heater shown embodies essentially the 65 stand A, a reflector or radiator B pivotally supported for vertical adjustment by the stand A, a heating element C operatively associated with the reflector or radiator B, and a guard or screen member D which extends 70 over the front of the reflector or radiator B.

The stand A may be formed of a casting, or otherwise produced if desired, and comprises a base 1 having an upwardly and rearwardly curved standard or post 2, which as 75 shown, is preferably hollow and an integral part of the base, which base is likewise hollow. The upper end of the post or standard 2 is open, enlarged, and shaped to provide a seat 3 for the semi-spherical protuberance or 80 projection 4 of a casing 5, the latter of which is secured in any suitable manner to the back of the radiator or reflector B. The projection 4 is pivotally connected preferably upon opposite sides as at 6 with the seat 7 formed 85 upon the standard or base 2, the pivotal connections being such that the semi-spherical projection will have close frictional engagement with the seat sufficiently to hold the reflector of the radiator in adjusted position. 90 The casing 4 is shown as circular and is secured upon the central portion of the reflector or radiator B in such manner that there is provided a dead air space E between the wall of the reflector and outer wall of the 95 casing 5. Thus it may be said that the reflector is double-backed or provided with a false back, and this construction is desirable in order to prevent the parts rearwardly of the reflector and heating element, from becoming heated to such an extent that there will be any possibility of accidental conflagration.

The reflector or radiator B is preferably formed of some light metal capable of being 105 highly polished, and which is best calcu-

lated to oppose heat absorption and provide for full reflection or radiation; for example, copper and like metals may be well used. As shown, the reflector is concavo-convex, and an essential requirement is that it be concave for the most part upon its reflecting surface. I have discovered that by providing a parabolic or substantially parabolic curve the best results can be obtained as to heat radiation and reflection, and in addition, that by providing what might be termed a central convexity or protuberance which forms two parts of the curve in the meeting thereof, the results as to effective heat radiation or reflection provided by the ordinary parabolic or substantially parabolic surface, are greatly enhanced. To this end I preferably employ a concavo-convex body of the reflector B which is generally designated 8, and in addition, a central cusp-like portion generally designated 9; and as a result the reflecting or radiating surface is a surface of revolution formed by the rotation of a parabola, or substantially a parabola; therefore there is formed a concave surface with the central cusp. It is to be understood that the term "cusp" as used relates to a portion or point formed by two parts of a curve meeting and may be applied to designate projecting points formed by the meeting of small arches or circles. The peripheral portion of the body 8 of the reflector is annular and curved rearwardly and slightly upwardly preferably so as to provide an annular flange-like portion 10, which portion forms an annular channel 11 that opens upon the rear face of the reflector. Preferably there is provided an outwardly extending flange 12 formed as a continuation of the portion 10 and which extends at approximately right angles to said portion 10 in a substantially vertical plane. This flange 12 may be separate but is preferably integral and a part of the metal of which the reflector is formed. The outer edge of the flange 12 may be beaded as at 13 and, as shown, the bead is formed of a separate strip bent around the outer edge of the flange, but said bead may be otherwise formed if so desired, the provision thereof being for the purpose of reinforcing the flange 12 and adding to the ornamental appearance thereof. The flange 12 is shown as being octagonal in shape, and this formation thereof adds to the ornamental appearance of the heater as a whole. However, other shapes may be employed if so desired. In case the heater is accidentally overturned, the flange, that is, the head 13 thereof, will rest upon the floor or object upon which the same engages, and as this point is removed from the source of heat all possibility of accidental conflagration or injury to the reflector is eliminated.

The heating element C is preferably annular and located substantially at the focus of the reflector. The annular element practically surrounds the cusp 9 and may be said to be concentric with the focus of the curve of the reflector. In this way heat produced by the entire surface of the heating element itself is radiated directly against the greater part of the reflector, with the result that highly efficient heat radiation and reflection is provided, much more so than where the heating element is disposed in positions other than the one hereinbefore described relative to the particularly shaped reflector. The element C consists preferably of a helix or helical coil 14 of high resistance wire, the coil being annular. This helix or coil 14 is supported by a porcelain ring 15 which upon its periphery for the most part of the circumference thereof is concaved or grooved as at 16 so as to snugly accommodate the helix 14, and as shown the helix partially surrounds this ring. Upon its lower side the ring is enlarged or formed with a lug or flange as at 17, and bolts 18 and 19, which are carried by the reflector B, pass through this portion 17 of the ring and provide for the supporting of the ring in the above described position. The two ends of the coil or helix 14 are secured upon the bolts 18 and 19 by means of nuts 20. There is provided an opening 21 in the lower side of the reflector B and a porcelain or other insulation material plug 22 is mounted within said opening, said plug being provided with an annular outwardly extending flange 23 which acts as a shoulder and abuts the reflecting face of the reflector in order to provide for a secure fitting of the plug in position. The bolts 18 and 19 are extended through this plug 22 and upon their rear ends have electrical conductors 24 secured thereto, the securing being effected through nuts 25 preferably. There may be provided washers 26 which are located between the ring 15 and opposed end of the plug 22. In order to hold the coils of the helix 14 securely in place and to hold the helix itself firmly upon the supporting ring 15 porcelain cement may be applied to these two elements of the heating means, and in addition tie members 27, which tie members are inserted through openings 28 in the ring 15, at suitable intervals and around coils of the helix, may be used. The tie members 27 are preferably constructed similarly to cotter keys, so that after being properly positioned the ends may be separated upon the inner side of the ring 15 to secure them in place. It is to be further noted that the ends of the coils of the helix, substantially abutting the enlarged portion or lug 17 of the ring 15, are securely and firmly held upon the supporting ring therefor, making a rigid compact heating element as a whole. The conductors 24 extend upwardly through the chamber or space 130

E and out through a longitudinal slot, 29 formed in the projection or protuberance 4, said slot 29 being in communication with the hollow standard 2. The conductors 24 pass 5 through standard 2 and are connected at a point substantially at the base 1 of the standard A, with a socket member 30, which latter is fitted in an opening 31 formed in the stand and projects outwardly from said stand. A contact plug 32 carrying conductors 33 may be inserted into the socket 30 so as to provide for electrical connections between the conductors 33 and 24. By disposing the cord attachment means, that is 10 to say, the socket 30, plug 32, and conductors 33 adjacent to the lower end of the base of the stand A, all possibility of conductors 33 becoming an obstacle in a room or apartment and resulting in tripping persons coming 15 in contact therewith accidentally, is eliminated, and further, the ornamental appearance of the heater as a whole, is enhanced.

The guard member D is preferably formed of suitably stiff wire strands or rods 34 25 which may extend over the front of the reflector B sufficiently to prevent injury to persons or objects coming into close contact with or falling against the heater or heating element itself, and to avoid the possibility 30 of fire in case of the upsetting of the heating element when in use. These wire strands 34 preferably radiate from the central portion of the reflector and as shown may be connected by suitable fastening elements as at 35 35, with the apex of the cusp 9 or the central portion of the reflector. In this connection it is noted that the cusp or central portion is not formed into a point but may be flattened upon the apex portion thereof, as shown at 36. From the center of the reflector these wires or rods 34 are preferably 40 arched outwardly and at their outer ends may be bent around a wire ring 37, said ring being disposed upon the outer face of the 45 flange portion 10, as shown. Thus, the flange acts as a support for the ring and outer extremities of the wires 34.

In the use of the heater when electrical energy is supplied to the heating coil, heat 50 thereby produced will be radiated from substantially the entire surface of the coil upon substantially the entire reflecting surface of the reflector B, and the reflection of heat will be in a direction which is substantially 55 horizontal; that is to say, the heat rays will be projected substantially in parallel lines, thus doing away with considerable loss of heat energy from convection. This phenomenon is due to the location of the heating element at the focus of the reflector, and the efficiency in heat reflection or radiation produced is due to the parabolic or substantially 60 parabolic reflecting surface having the central convexity or cusp taken in consideration with the annular heating element and

its disposition in concentric relation with the focus (which is also a circle) of the curve of the reflector. It has been found that heat rays radiated, projected and reflected by the heater of this invention are peculiarly intense and directly projected in an extremely expeditious manner and are far-reaching in their extent of projection and further, that a maximum heat may be reflected to the point of consumption with a remarkably low wattage 70 consumption of electrical energy. In this connection it will be noted that the wattage consumption can be varied by varying the diameter of the helix or heating coil, by varying the area of the resistance wire and 75 by the provision of two or more heating elements. It is to be further noted that the heating element can be replaced readily and easily by removing the two nuts 20 and withdrawing the ring 15 for supporting the heating coil from the bolts 18 and 19, no skilled labor being required. Likewise, the guard member D may be readily removed by simply withdrawing the fastening elements 35. As the reflector is pivotally mounted upon 80 the stand A it may be tilted into the desired position to reflect or project the heat in the desired direction and through frictional engagement of the stand with the element 4 the reflector will maintain its adjusted position. 85

Referring particularly to Figs. 4 and 5 wherein there is illustrated a modified form of the invention, F designates a reflector of the same construction as embodied in the 100 preferred form of the invention, and G designates a heating element supported by and associated with the reflector F in the same manner as is the heating element in the preferred form of the invention. The heating 105 element G comprises a supporting means therefor in the form of an annular ring 38 preferably formed of porcelain. This ring 38 is formed with a peripheral groove 39 in its outer face, the outer wall of the groove 110 being higher than the inner wall and serving as a flange 40. This flange 40 acts as a screen relative to the helix or helical coil 41 which is mounted within the groove, and prevents outward radiation of heat from the 115 coil, to the end that heat impinging upon and radiated onto the inner face of the flange 40 will be reflected rearwardly upon the reflector F and thence, projected outwardly from the reflector. It will thus be seen that 120 with this construction all possibility of loss of heat energy by convection is removed.

The heating element G is positioned relative to the cusp H of the reflector F in the same manner as is the preferred form of 125 heating element and is supported by bolts 42 mounted in an insulation plug 43, which plug is carried by the reflector F. Inasmuch as the mode of operation, general construction and relative arrangement of ele- 130

ments of this form are the same as in the preferred form, and the only modification is in regard to the construction of the support for the heating coil, further description is thought unnecessary.

Referring particularly to Figs. 6 and 7, wherein there is illustrated another modified form of the invention, J designates a reflector identical in construction with the reflectors of the other forms of the invention, and provided with a central cusp K. A heating element L surrounds the cusp K and is supported by the reflector J through the instrumentality of the bolts 44, which bolts are supported in the plug 45 carried by the reflector J.

The heating element of this form of the invention consists preferably in a flat split ring 46 of insulation material such as porcelain. A helical coil of resistance wire, or a helix 47 is wound around the ring 46, the ring passing through the coils of the helix. The ends of the coils are secured to the bolts 44 by means of nuts 48, and these bolts extend through the terminal portions of the split ring. There may be provided a series of elongated openings or slots 49 in the split ring 46 and these openings or slots allow for maximum heat radiation and prevent loss of heat radiation, as would be the case were the ring not provided with such openings. This form of the invention may be more desirable, subject to certain conditions of use, cost of production and requirements as to use. The operation of this form is the same as that of the preferred form of the invention, and the present form possesses all the advantages and efficiency of that of the preferred form.

The foregoing description and accompanying drawings embody the preferred types of the invention, and as I do not wish to be limited to these types, it is to be understood that I may make minor changes as to details of construction, size, shape, proportions of parts and elements of the invention, without departing from the true spirit and scope thereof, as defined herein and in the appended claims.

Having thus disclosed my invention, I claim and desire to secure by Letters Patent:

1. A heater, comprising a reflector having a reflecting surface for the most part concave and otherwise provided with a convex portion, and a heating element disposed substantially at the focus of said reflector.

2. A heater, comprising a reflector having a reflecting surface for the most part concave and otherwise centrally provided with a convex portion, a heating element disposed substantially at the focus of said reflector, and means for supporting the reflector.

3. An electric heater including a reflector formed with a concave portion extending annularly around a central axis and of such

a configuration that a section extending radially outward from the axis in any direction is substantially a parabola, and an annular heating element extending around the reflector and arranged at the focus thereof. 70

4. An electric heater including a reflector having a central convex portion surrounded by an annular concave portion which is substantially parabolical in section, and an annular heating element arranged at the focus 75 of the concave portion of the reflector.

5. An electric heater comprising a reflector having a central convex portion surrounded by an annular concave portion which is substantially parabolical in section, 80 a ring of insulating material extending around the concave portion of the reflector, an electrical resistance element supported by the ring, and insulated conducting posts extending outwardly from the reflector to the 85 ring and engaging the terminals of the resistance element.

6. A heater, comprising a reflector having a reflecting surface of revolution formed by the rotation of a parabola with axis parallel, 90 thus forming a concave surface with a central cusp, a heating element located substantially at the focus of said reflector, and a guard member extending over the face of and supported by the reflector.

7. An electric heater including a reflector having a central convex portion surrounded by an annular concave portion which is substantially parabolical in section, an annular heating element extending around the concave portion of the reflector and arranged concentric with the convex portion thereof, 100 said heating element being supported at substantially the focus of the concave portion of the reflector, and arched guard wires radiating outwardly from the central convex portion of the reflector. 105

8. An electric heater, comprising a reflector having a reflecting surface provided with a central substantially conical convex portion, and an annular concave portion surrounding the convex portion, providing a substantially parabolical curve, and a heating element concentric with the focus of the curve.

9. An electric heater, comprising a reflector having a substantially concave reflecting surface, an annular heating element located in concentric relation with the focus of the curve of the reflecting surface, an annular non-conducting ring upon which the heating element is mounted, and means for supporting said ring, connected with the reflector.

10. An electric heater, comprising a reflector having a substantially concave reflecting surface, an annular heating element located in concentric relation with the focus of the curve of the reflecting surface, an annular non-conducting ring upon which the

- heating element is mounted, and means for supporting said ring connected with the reflector; said ring having a flange upon its outer edge, which flange extends in front of the heating element to prevent outward projection of heat from the element.
11. An electric heater, comprising a reflector having a substantially concave reflecting surface and provided centrally with a convex portion, an annular heating element mounted in concentric relation to the focus of the curve of the reflecting surface, means to support said element connected with the reflector, and a guard member extending in front of the reflecting surface and heating element, said guard member being attached to the convex portion at the apex thereof and engaged with the reflector adjacent the outer edge of the reflecting surface of the reflector.
12. An electric heater, comprising a reflector having a substantially concave reflecting surface and provided centrally with a convex portion, an annular heating element mounted in concentric relation to the focus of the curve of the reflecting surface, means to support said element connected with the reflector, and a guard member extending in front of the reflecting surface and heating element, said guard member being attached to the convex portion at the apex thereof and engaged with the reflector adjacent the outer edge of the reflecting surface of the reflector; said reflector having a false back providing an air space, a projection carried by the false back, a stand for supporting the reflector and having a seat for the projection, and means to pivotally

connect the projection with the stand at said seat.

13. An electric heater, comprising a reflector, a heating element associated with the reflector, said reflector having a false back providing a dead air space, a semi-spherical projection carried by the false back, a stand for the reflector, said stand having a seat adapted to be frictionally engaged by the projection, and means to pivotally connect the projection with the stand at the seat.

14. An electric heater, comprising a reflector, a heating element associated with the reflector, said reflector having a false back providing a dead air space, a semi-spherical projection carried by the false back, a stand for the reflector, said stand having a seat adapted to be frictionally engaged by the projection, and means to pivotally connect the projection with the stand at the seat; said stand and projection being hollow, and electric conductors electrically connected with the heating element, said electric conductors being mounted within the air space, projection and hollow stand, said projection having an opening therein communicating with the hollow stand, and means of attachment located near the base of the stand for electrically connecting the conductors with the source of electricity.

In testimony whereof, I have signed my name to this specification in the presence of two subscribing witnesses.

ALFRED R. HUNTINGTON.
